ATTACHMENT MEMBER FOR SCAFFOLDING CROSS BRACES

Merle P. French, 90 Maywood Road, New Rochelle, N.Y.

Filed May 13, 1960, Ser. No. 60,573

Term of patent 14 years

(Cl. D54—1)

Fig. 1.

Fig. 2.

Fig. 3.

Fig. 4.

Fig. 5.

FIG. 1 is a front elevational view of an attachment member for scaffolding cross braces showing my new design;

FIG. 2 is a right side elevational view of FIG. 1;

FIG. 3 is a rear elevational view;

FIG. 4 is a top plan view; and

FIG. 5 is a bottom plan view thereof.

I claim:

The ornamental design for an attachment member for scaffolding cross braces, substantially as shown.
